US00D622435S

(12) **United States Design Patent**
Recore et al.

(10) **Patent No.:** US D622,435 S
(45) **Date of Patent:** ** Aug. 24, 2010

(54) **LIGHT FIXTURE**

(75) Inventors: **Chad Recore**, Peru, NY (US); **Thomas Schwab**, Innsbruck (AT)

(73) Assignee: **Schonbek Worldwide Lighting Inc.**,
Plattsburgh, NY (US)

(**) Term: **14 Years**

(21) Appl. No.: **29/353,607**

(22) Filed: **Jan. 12, 2010**

(51) LOC (9) Cl. **26-03**

(52) U.S. Cl. **D26/85**; D26/128

(58) Field of Classification Search D26/85-91,
D26/118, 128; 362/147, 404-408, 432

See application file for complete search history.

(57) **CLAIM**

The ornamental design for a light fixture, as shown and described.

DESCRIPTION

This application is related to commonly assigned, concurrently filed U.S. application Ser. No. 29/353,601.

FIG. 1 is an isometric view of the light fixture of the present invention;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof;

FIG. 7 is a bottom plan view thereof;

FIG. 8 is an isometric view of a smaller second embodiment, otherwise identical to the first embodiment; and,

FIG. 9 is an isometric view of a larger third embodiment, otherwise identical to the first embodiment.

The broken line showing is for illustrative purposes only and forms no part of the claimed invention.

1 Claim, 9 Drawing Sheets
